9198

UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of **Design No. 15,104, dated June 24, 1884.**

Application filed May 12, 1884. Term of patent 3½ years.

To all whom it may concern:

Be it known that I, MARY TURNER, of the city, county, and State of New York, have invented and produced a new and original Design for a Pattern of a Lady's Costume, (numbered 9,198;) and I do hereby declare that the engraved prints accompanying this specification convey to any one accustomed to using paper patterns a clear understanding of how the garment made up by the pattern will appear.

The design shows a round walking-skirt and a waist. The skirt displays a deep right front drapery, rounding away at its lower edge, and exhibiting gatherings at its front and back edges; a left front drapery, that appears to overlap the right front drapery, falls in a deep point at its lower front corner, and exhibits gatherings in its upper and back edges; and a deep full back drapery that exhibits a deep

looping at its center and draping plaits in its front edges. The waist displays outer fronts that exhibit gatherings at the shoulders and lower edges, and expose closely-fitted under-fronts above the bust, a closely-fitted back, a standing collar, and coat-sleeves showing gathers and a high roll at the shoulders, and displaying the wrists reversed in cuff form, with a flare at their back edges.

What I claim as my invention, and desire to secure by Letters Patent, is...

The design for a lady's costume, as shown in the engraved prints accompanying this specification.

MARY TURNER.
